BALL PLUG SETTING TOOL

Edward T. Gilda, St. Louis, Mo., assignor to Carter Carburetor Corporation, St. Louis, Mo., a corporation of Delaware

Application August 23, 1950, Serial No. 181,060

1 Claim. (Cl. 78—60)

1

This invention relates to tools for setting ball plugs in the ends of passages, for instance, in carburetors.

The passages of carburetors must be drilled through an outer surface and, frequently, closed by a plug, usually a ball plug. These plugs are small and the handling thereof, including guiding the plug into the end of its passage and setting the same, is, accordingly, difficult.

The main object of the present invention is to provide a tool which will select a ball from a stock thereof, stably hold the same while being guided into the end of a passage or orifice to be plugged, and direct a blow of a hammer against the ball for setting the same.

Another object is to provide a tool which in addition to guiding and setting the ball, will lock the same in position.

These objects and other more detailed objects hereafter appearing are attained by the device illustrated in the accompanying drawing in which:

Fig. 1 is a longitudinal section through the tool, showing a ball plug in position to be set.

Fig. 2 shows the plunger at the end of its ball driving stroke.

Fig. 3 is an enlarged, detail section showing the ball receiving end of the tool applied to a passage to be plugged.

Fig. 4 is a similar view, but showing the ball driven into position.

Fig. 5 is a detail section similar to Figs. 3 and 4 but showing a modification.

Fig. 6 is a section similar to Fig. 5, but showing the ball plug driven into position.

The tool comprises a tubular handle sleeve 8 having a central bore 9 slidably receiving a plunger member 10 with a reduced portion 11 working in a similarly reduced portion 12 of the handle bore. A coiled spring 13, compressed between the handle and plunger, urges the plunger toward the right, but this movement is limited by a set screw 14 on the plunger which engages the edge of a slot 15 in the handle member. In the normal, rest position of the tool, the inner end 16 of the plunger, as best seen in Fig. 3, is positioned inwardly of the corresponding end of the handle member, a distance slightly less than the diameter of the bore of the handle member at this end, but greater than the radius of the bore to form a cup for stably receiving a ball plug 19. The end of the handle member has a tapered outer surface as at 20, to facilitate the guiding of a plug into the pocket from a stock of these parts. The plunger, at its outer end, is provided with a head 21 which, in

2

the rest position as in Figs. 1 and 3, is spaced from the corresponding end 22 of the handle member, a distance approximately the same as the depth of plunger end 16 within the handle member, as just described.

Plunger 10 is permanently magnetized so that a metallic ball will adhere thereto.

In operation of this form of the invention, the tool is thrust into a stock of ball plugs, whereupon one of the plugs will adhere thereto, as in the figures. The ball will be stably held within the small cup formed at the tapered end of the tool, more than half thereof being within the cup, so as to be readily guided on the surface of the work and into the end of the passage to be plugged without the danger of the ball rolling or being forced from its position on the tool. The tool is then held properly angled with relation to the work and the head 21 given a sharp blow with a hammer to set the ball. The engagement of the head with the corresponding end 22 of the handle member, insures proper setting of the ball, as shown in Fig. 4. While this ball projects slightly, it may be set flush with the surrounding surface by constructing the plunger so as to be flush with the end of the handle sleeve at the end of the driving stroke.

In Figs. 5 and 6, the bore at the end of the tool is made of somewhat greater diameter than the ball it is intended to receive and a depression 24, shaped as a portion of the surface of a sphere, is formed in the end of plunger 10a. As in the previous form, the projecting portion of ball 19a may be guided into a passage to be plugged and the plunger thereupon given a sharp blow. In this form, the head at the outer end of the plunger is spaced somewhat farther from the end of the handle member, than in the first form, so that at the end of the plug setting stroke, the plunger will protrude slightly beyond the end of the handle member, as at 25. Being somewhat wider than the ball and its receiving passage, the plunger will strike the periphery of the ball receiving passage somewhat upsetting the metal, as indicated at 26, to securely lock the ball in position. The same function may be served using the first form by making the forward tip of the handle member sufficiently small and by giving the outer end of the plunger a hard enough blow to cause the end of the handle member to slightly upset the metal about the plug orifice.

The exclusive use of all modifications as come within the scope of the appended claims is contemplated.

I claim:

A ball plug guiding and setting tool comprising a body with an elongated, longitudinal bore and a first tapered end, a magnetized plunger slideable in said bore, said plunger having a diameter greater than the diameter of a ball plug and having a spherical recess in its end corresponding to the curvature of the plug, a spring stressed between said body and said plunger and urging said plunger in the direction to draw one end thereof within said tapered end of said handle, stops on said body and said plunger limiting the spring produced movement thereof to a rest position with said mentioned end of said plunger a distance inside said bore less than the diameter thereof to form a cup for stably receiving a ball plug from a stock into which the tool is directed, the other end of said plunger projecting oppositely from said body a distance slightly greater than the diameter of said bore, and a shoulder on said oppositely projecting end of said plunger for striking the adjacent end of said body to limit the plug setting stroke of said plunger to thereby limit the most advanced po-

sition of said plunger in the plug setting direction to a position slightly beyond the tapered end of said body for first setting the received ball plug and then swaging the edge of the plug receiving opening to secure the plug in position.

EDWARD T. GILDA.
